Primary Examiner — Bridget L Eland(74) *Attorney, Agent, or Firm* — Ward and Smith, P.A.;
Ryan K. Simmons(57) **CLAIM**

The ornamental design for a foundation guide seating site, as shown and described.

DESCRIPTION

FIG. 1 is a perspective view of a foundation guide seating site showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a cross-sectional view of the foundation guide seating site of FIG. 6 along line 8-8.

In the Figures, the broken lines are for the purpose of illustrating environment and form no part of the claimed design.

1 Claim, 6 Drawing Sheets# US D1,006,225 S
